UNITED STATES PATENT OFFICE.

FREDERICK J. MULHERN, OF TROY, NEW YORK.

GARBAGE RECEPTACLE.

Application filed July 12, 1926. Serial No. 121,749.

Reference may be had to the accompanying drawings, and the reference characters marked thereon, which form a part of this specification. Similar characters refer to 5 similar parts in the several figures therein.

Certain objects of the invention are to provide a stable covered garbage-receptacle which can be opened by foot pressure, and will be automatically closed when the foot 10 pressure is removed; to simplify and facilitate the construction of the device; and to provide for the ready separation from the container, of the cover and its operating mechanism.

Other objects will appear in connection 15 with the following description.

Fig. 1 of the drawings is a view in front elevation of a garbage receptacle embodying my invention showing the treadle-bail de- 20 pressed and the cover open.

Fig. 2 is a view in side elevation of the same with the cover closed.

Fig. 3 is a top plan view of the same.

Fig. 4 is a vertical section of a broken- 25 away portion of the same taken on the broken line 4—4 in Fig. 3.

Fig. 5 is a vertical section of the same taken on the broken line 5—5 in Fig. 4.

Referring to the drawings wherein the 30 invention is shown in preferred form, the body of the receptacle comprises a container, 1, shown in the form of a flaring pail for convenience in nesting the containers together for shipment.

Mounted upon the side of the container, 35 is a bracket, 2, having two laterally projecting ears, 3, and 4, each being formed with a downwardly open trunnion-bearing, 5, and one of said ears, 3, being formed with a circular perforate bearing opening, 6.

A lever, 7, is pivotally mounted upon the bracket, 2, by means of a hook-end, 8, on 40 the lever, which in certain positions of the lever can be readily engaged with or disengaged from the bearing opening, 6.

When the hook-end, 8, of said lever is in engagement with the bearing opening, 6, the lever is pivotally mounted upon the bracket, 2, with provision for lost motion due to the 45 fact that the hook-end, 8, of the lever is flat, while the bearing opening, 6, is circular.

A cover, 9, for the container has a laterally projecting lifting-arm, 10, formed with a U-shaped bend, 11, and a shaft, 12, is secured within said bend with its ends projecting to form trunnions, 13, engageable

with the respective downwardly-open bearings, 5, in the ears, 3 and 4, of the bracket, 2.

The lower member, 10^a, of the cover-lift- 60 ing arm, 10, extends inwardly beyond the axis of the shaft, 12, across the path of the lever, 7, and is preferably bent to form a downwardly open groove, 10^b, to receive the lever.

The construction is such that the upward 65 movement of the lever, 7, serves to raise or open the cover.

When it is desired to open the container, the lever, 7, can be raised by depression of a treadle-bail, 28, one end of which is se- 70 cured to the lever by means of the screw, 14, in engagement with an offset, 15, on the lever; the other end of the bail being piv- 75 otally mounted on the container by detach- able engagement of a hook, 16, on said other end with a bearing-opening in a bracket, 17, on the container opposite the bracket, 2.

The lever, 7, has another offset, 18, en- 80 gageable with an offset, 19, on the cover- lifting arm, 10, to limit the upward move- ment of the cover.

The lever, 7, is also formed with a mem- 85 ber, 20, engageable with the ear, 4, on bracket, 2, to limit the upward movement of the lever, and to thus limit the downward move- ment of the treadle-bail, 28, to prevent the bail from being depressed sufficiently to en- 90 gage and mar or otherwise injure the container.

The operation of the device is as follows: 90

When access to the container is desired, as for depositing garbage therein, the user 95 presses a foot down upon the treadle-bail, thereby depressing the bail and by engage- ment of the bail with the offset, 15, on the lever, serving to raise the lever, and by en- gagement of the lever with the overhang- 100 ing member, 10^a, of the cover-lifting arm, 10, serving to raise or open the cover to the position shown in Fig. 1.

When the foot pressure is removed from the treadle-bail, the parts automatically return to normal position as shown in Figs. 2 and 4, and as indicated by dotted lines 9^a and 28^a in Fig. 1.

To remove the bail, 28, the lever-raising end of the bail is detached by removing the screw, 14, whereupon the other end of the bail can be readily unhooked from the bracket, 17.

The lever, 7, can then be swung down until its hook-end, 8, opens upwardly, whereupon

100

105

110

110

it can be downwardly withdrawn from the bracket ear, 3, as indicated by dotted lines 7^a in Fig. 2.

The cover can be removed by swinging it upwardly, as to the position indicated by dotted lines, 9^b, in Fig. 1, and then moving it outwardly and downwardly to slide the trunnions, 13, out of the open bearings, 5, in the bracket-ears, 3 and 4, the bail, 28, being at the same time raised to depress the lever, 7, out of the path of the bent end of the lower member, 10^a, of the cover-lifting arm, 10.

The parts can thus be readily assembled for use, or disassembled for packing and shipment or other purposes.

The axis of the cover formed by the trunnions, 13, is at approximately right angles to the axis of the bail, 28, both axes being horizontal.

In practice, however, these axes are slightly inclined to one another in order to have the axis of movement of the treadle-bail extend diametrically of the container.

25 The lost motion provided for in the engagement of the hook end, 8, of the lever, 7, with the bearing, 5, in the ear, 3, overcomes any tendency of the parts to bind due to this slight inclination of one of said axes relatively to the other, as well as that due to the fact that the groove, 10^b, in the cover-lifting member, 10^a, moves in an arcuate path about the axis of the trunnions, 13.

35 To facilitate the operation of the lever, 7, to raise the cover, 9, I prefer to provide the lever with an upwardly convexed or cam shaped surface as shown at 21.

The bail, 28, can be swung upwardly to 40 vertical position as indicated by dotted lines in Fig. 2, to serve as a lifting bail for the container with the cover attached thereto or detached therefrom.

The bent end of the cover-lifting-arm member, 10^a, terminates at a point farther removed from the center of the cover than is the periphery of the cover as indicated by dotted lines α — α in Fig. 4, this making it possible to stack or nest the covers closely 50 one within another with the cover-lifting arms, 10, in disalignment with one another, for convenience and economy in transportation.

I do not wish to be limited to the constructions shown and above described, as, for certain purposes of the invention, various changes may be made in the form and arrangement of various parts of the device without departing from the spirit of the invention.

What I claim as new and desire to secure by Letters Patent is:

1. In a device of the class described and in combination, a container; a cover hinged 65 upon the container; and having a cover-

lifting member provided with a downwardly open groove substantially parallel with the hinge axis on the inner side thereof; and a treadle-bail pivotally mounted on the container and having a member projecting from one of its ends beyond the pivotal connection engageable with said groove in the cover-lifting member, whereby the cover is raised by depression of the treadle-bail.

2. In a device of the class described and 75 in combination, a container; a cover hinged upon the container and having a cover-lifting member provided with a downwardly open groove substantially parallel with the hinge axis on the inner side thereof; and a treadle-bail pivotally mounted on the container and having a member projecting from one of its ends beyond the pivotal connection engageable with said groove in the cover-lifting member, whereby the cover is 80 raised by depression of the treadle-bail, the pivotal connection of said end of the bail providing for lost motion to permit lateral rocking movement of said projection transversely of the axis of its pivotal upward 85 movement.

3. In a device of the class described and in combination, a container; a bracket mounted upon the container; a lever pivotally mounted on a horizontal axis on said bracket, said lever having an upwardly convexed surface and having an offset; a hinged cover having a lifting arm projecting across the path of said convexed surface whereby the cover is raised by upward movement of the lever; a bail having one end connected with said lever in engagement with the offset thereon to raise the lever, the other end of the bail being pivotally mounted on the container.

4. In a device of the class described and 105 in combination, a container, a bracket mounted upon the container; a lever pivotally mounted on a horizontal axis on said bracket, said lever having an upwardly convexed surface and having two offsets; a hinged cover having a lifting arm projecting across the path of said lever, whereby the cover is raised by upward movement of the lever; a bail having one end connected with said lever in engagement with one of 110 said offsets thereon to raise the lever, the other end of the bail being pivotally mounted on the container; and an offset on the lifting arm of the cover engageable with the other offset on the lever to limit the upward movement of the cover.

5. In a device of the class described and in combination, a container; a bracket mounted on the container and having a laterally projecting apertured ear; a lever having a hook-end removably engageable with the aperture in said ear of the bracket to form a hinge-connection therewith and also having an offset; a cover removably hinged upon the container and having a lift- 125 130

ing member projecting across the path of upward movement of said lever; and a bail having one end detachably pivotally connected with said lever in engagement with the offset thereon to raise the lever, the other end of the bail being pivotally mounted on the container.

6. In a device of the class described and in combination, a container; a bracket mounted on the container and having two laterally projecting ears; a lever having a bail attached thereto pivotally connected with one of said ears and having two offsets, and a member engageable with the other ear to limit the upward movement of the lever and the downward movement of the bail; a cover hinged upon said ears and having a lifting member projecting across the path of said lever, and also having an offset engageable with one of the offsets on the lever to limit the upward movement of the cover; and a bail having one end detachably connected with the lever in engagement with the other offset thereon to raise the lever, the other end of the bail being pivotally mounted on the container.

7. In a device of the class described and in combination, a container; a bracket mounted on the container and having two ears each formed with a downwardly open trunnion-bearing; a lever pivotally mounted on one of said ears; a cover having a laterally projecting lifting arm; oppositely projecting trunnions on the cover-lifting arm

removably engageable with the respective downwardly open bearings in the ears of said bracket, said arm including a member extending inwardly beyond the axis of said trunnions across the upward path of said lever; and a bail having one end connected with said lever to raise the lever by depression of the bail, the other end of said bail being in pivotal connection with the container.

8. In a device of the class described and in combination, a container; a bracket mounted on the container and having two ears each formed with a downwardly open trunnion-bearing; a lever pivotally mounted on one of said ears; a cover having a laterally projecting lifting arm; oppositely projecting trunnions on the cover-lifting arm removably engageable with the respective downwardly open bearings in the ears of said bracket, said arm including a member extending inwardly beyond the axis of said trunnions across the upward path of said lever and provided with a downwardly open lever-engaging groove on the inner side of and substantially parallel with the axis of said trunnions; and a bail having one end connected with said lever to raise the lever by depression of the bail, the other end of said bail being in pivotal connection with the container.

In testimony whereof, I have hereunto set my hand this 9th day of July, 1926.

FREDERICK J. MULHERN.
